Primary Examiner — Holly Baynham

(57) **CLAIM**

The ornamental design for an ornament for a purse, jewelry box, gift box, lunch box and/or multi-purpose container, as shown and described.

DESCRIPTION

FIG. 1 is a front elevation view depicting my new, original design

FIG. 2 is a back elevation view of depicting my new, original ornamental design, in the open position

FIG. 3 is a back elevation view depicting my new, original ornamental design, in the closed position

FIG. 4 is a left side elevation view depicting my new, original ornamental design; a right side elevation view is not included as it is a mirror image of the left side elevation view; and, FIG. 5 is a perspective view depicting my new, original ornamental design.

A bottom view depicting my new, original ornamental design is not included as the bottom is flat and contains no surface ornamentation.

The characteristic feature of novelty and/or non-obviousness lies in the uniqueness of the design, which while it may appear to be applied to a doll, is in fact an ornamental design applied to a useful containment object, such as a purse, jewelry box, gift box, lunch box and/or multi-purpose container. It is not obvious that the skirt opens to reveal any of the aforementioned useful containment objects. The characteristic feature of novelty and/or non-obviousness lies also in the fact that the design stands alone, without the aid of exterior supports.
